UNITED STATES PATENT OFFICE.

GEORGE W. HOOPER, OF GREENE, MAINE.

IMPROVEMENT IN DOUBLE-ACTING FORCE-PUMPS.

Specification forming part of Letters Patent No. 178,057, dated May 30, 1876; application filed April 10, 1876.

To all whom it may concern:

Be it known that I, GEORGE W. HOOPER, of Greene, in the county of Androscoggin and State of Maine, have invented a new and useful Improvement in Double-Acting Force-Pump, of which the following is a specification:

Figure 1 is a side view of my improved pump, partly in section, through the line *x x*, Fig. 2 is a horizontal section of the same, taken through the line *y y*, Fig. 1.

Similar letters of reference indicate corresponding parts.

The object of this invention is to furnish an improved double-acting force-pump, simple in construction, convenient in use, easily operated, and effective in operation, throwing a steady stream.

The invention will first be described in connection with drawing, and then pointed out in the claims.

A is the pump-cylinder, to the ends of which are bolted the heads *B*, and within which works the piston *C*. The piston *C* is cast solid, and is made with parallel ring-flanges, which project nearly to the inner surface of the cylinder *A*, and which form a square groove around the convex face of the piston to receive the packing *D*. The packing *D* is made of strips of leather bent edgewise into the groove of the piston *C*, enough pieces of leather being used to fill said groove snugly. When the packing *D* becomes worn it may be renewed by taking off one of the heads *B*, and removing the piston *C*. The piston-rod *E* passes out through a hole in the upper head *B*, which hole is made larger than the piston-rod *E*, to give it the necessary lateral play. *F* is a plate of steel, or other hard metal, having a hole formed through it, into which the piston-rod *E* fits snugly. The plate *F* is smaller than the cavity in which it is placed, so that it may be moved laterally by the lateral movement of the piston-rod *E*. The plate *F* is kept in place by a ring-plate, *G*, which is bolted to the head *B*, and rests upon a shoulder of said head, which shoulder is made a little higher than the thickness of the packing-plate *F*, so that it cannot bind the said plate *F*. To the upper end of the piston-rod *E* is attached a cross-head, *H*, to the ends of which are pivoted

two small rollers, *I*, which roll along grooves in the inner sides of the guide-bars *J*. The guide-bars *J* are parallel with each other, and are pivoted to the ends of two parallel bars, *K*, which are pivoted at their centers to the pump-tube *L*, so that by turning the bars *K* upon their pivots the guide-bars *J* may be adjusted closer together or farther apart, and will be held all the time parallel with each other. To the cross-head *H* is pivoted the lower end of the connecting-bar *M*, the upper end of which is pivoted to the head of a bolt, *N*, that passes through the end of the pump-handle *O*, and is secured to it by a nut. The handle *O*, at a little distance from the bolt *N*, is slotted longitudinally to receive the fulcrum-bolt *P*, the head of which is pivoted to an arm, *Q*, attached to the pump-tube *L*. By this construction the fulcrum-point of the handle *O* may be adjusted by adjusting the bolt *P* in the slot of the said handle *O*. To the side of the cylinder *A* is attached, or upon it is formed, a valve-box, *R*, from the ends of which openings *S S'* lead into the end parts of the cylinder *A*, and openings *T T'* leading into the bore of the pump-tube *L*. In the box *R* is cast a twisted partition, *U*, forming two passages, *V V'*,—the one, *V*, leading from the opening *S'*, leading into the cylinder *A*, to the opening *T*, leading into the pump-tube *L*, and the other, *V'*, leading from the opening *T'*, leading into the pump-tube *L*, to the opening *S*, leading into the cylinder *A*. *W W'* are two valves interposed between the openings *S S'* and the openings *T T'*—the one, *W*, opening toward the opening *T*, and the other, *W'*, opening toward the opening *S'*. *X X'* are two valves interposed between the openings *S S'* and the passages *V V'*—the one, *X*, opening toward the opening *S*, and the other, *X'*, opening toward the passage *V*. As it is advisable that the piston-rod *E* should be close to the pump-tube *L*, the cylinder *A* is let into said tube *L*, where it is secured in place by rods *Y*, bent to fit upon the pump-tube *L*, and the ends of which are secured to flanges formed upon the cylinder *A* and box *R*. The rods *Y* keep the cylinder *A* and box *R* in place, and at the same time they strengthen the pump-tube *L* where it is weakened by letting the said cylinder into it. The bore of the tube *L* is closed by a

plug, l' , driven into a hole formed in said tube between the openings T T' , and made a little larger than said bore. The water enters the opening T' from the lower part of the tube L , and may enter the said tube through an opening between the plug l' and opening T' , or at any desired distance below said opening T' .

In using the pump, as the piston C moves downward a vacuum is formed above it, and the water is forced by atmospheric pressure in through the opening T' , up through the passage V' , forces open the valve X , and passes through the opening S into the upper part of the cylinder A . At the same time the water in the lower part of the cylinder A is forced out through the opening S' , forces open the valve X' , passes up through the passage V , through the opening T , into the pump-tube L , and out through it. As the piston C moves upward the water passes in through the opening T' , opens the valve W' , and passes in

through the opening S' , into the lower part of the cylinder A . At the same time the water above the piston C is forced out through the opening S , forces open the valve W , and passes through the opening T into the pump-tube L , and out through it.

Having thus described my invention, what I claim as new, and desire to secure by Letters Patent, is—

1. The combination of the cross-head H , pivoted bar M , bolt N , slotted handle O , and arm Q , as and for the purpose described.
2. The combination of the adjustable bars K with the grooved guide-bars J , the rollers I , and the cross-head H , attached to the piston-rod E of a pump, substantially as herein shown and described.

GEORGE W. HOOPER.
